UNITED STATES PATENT OFFICE.

KASIMIR STACHOWSKI, OF CHICAGO, ILLINOIS.

DESIGN FOR A SOCIETY BADGE OR BUTTON.

No. 37,804.

Specification for Design.

Patented Feb. 6, 1906.

Application filed November 22, 1905. Serial No. 288,600½. Term of patent 7 years.

To all whom it may concern:

Be it known that I, KASIMIR STACHOWSKI, a citizen of the United States, residing at Chicago, in the county of Cook and State of Illinois, have invented a new, original, and ornamental Design for a Society Badge or Button, of which the following is a specification.

The accompanying drawing illustrates a design in accordance with my invention.

I claim—

The ornamental design for a society badge or button, as shown.

KASIMIR STACHOWSKI.
